UNITED STATES PATENT OFFICE.

EUGENE H. TAYLOR, OF HYDE PARK, MASSACHUSETTS.

PAPER-BOX MACHINE.

1,116,759.

Specification of Letters Patent.

Patented Nov. 10, 1914.

Application filed March 5, 1912. Serial No. 681,702.

To all whom it may concern:

Be it known that I, EUGENE H. TAYLOR, a citizen of the United States, residing at Hyde Park, county of Norfolk, State of Massachusetts, have invented a certain new and useful Improvement in Paper-Box Machines, of which the following is a specification, reference being had therein to the accompanying drawings.

10 My present invention relates to paper box machines of the class known as "topping machines" by means of which a rectangular piece of paper is applied to the surface of a cover or to the bottom of the box itself leaving a narrow margin around the edge of the box or cover.

The machine embodying my invention is in general of the type shown and described in the patent to Schoettle and Garrett, No. 20 1,032,781, dated July 16, 1912, in which there is shown and described a machine having a rest on which the cover or box is placed, feeding mechanism for supplying the paper, and jaws for severing the paper, the jaws 25 and the rest being connected in such a manner that the pressure exerted by the operator on the covering paper to cause the covering paper to adhere to the box or top depresses the rest and causes the knives to sever the

30 covering paper at the proper point. In the machine shown in said application the paper is drawn out by the depression of the box rest. I find that this action prevents satisfactory working of the machine, accordingly

35 I have so constructed the present machine that the paper remains stationary during the cutting. Furthermore to obtain satisfactory action of the severing mechanism under these conditions I find that the knives should op-

40 erate in the same manner as a pair of scissors, *i.e.* the cutting point should travel across from one side of the paper to the other. It is also desirable that the paper shall not be displaced vertically by the action of the 45 knives. To accomplish this the cutting point must always be on the same level.

The machine embodying my present invention provides means for cutting the paper as stated.

50 It also provides means for adjusting the length of the paper between the paste roll and the jaws so that the paste or other adhesive on the paper shall be exposed to the air for a variable length of time sufficient to 55 allow the adhesive to dry and become tacky

which is the proper condition for application to the box.

Novel means are also provided to enable the paper to be threaded through the machine more easily.

60 The invention will be fully understood by reference to the following specification taken in connection with the accompanying drawings, and the novel features thereof are pointed out and clearly defined in the claims 65 at the close of this specification.

Referring to the drawings, Figure 1 is a side elevation of a machine embodying my invention. Fig. 2 is a front elevation of the machine shown in Fig. 1. Fig. 3 is a top 70 plan view. Fig. 4 is a section on line 4-4 Fig. 2 on a somewhat enlarged scale. Fig. 5 is a detail of the adjustable guide finger. Fig. 6 is a view of the knives showing their 75 respective inclinations.

In the drawings, a suitable frame for the machine designated at A, is provided to support the various working instrumentalities.

At 11 is indicated the reel upon which the 80 roll of covering paper is supported. The web of paper is designated 12. After leaving the reel, the paper passes under an adjustable guide 13, pivoted at 14 and provided with a finger 15 coöperating with a corresponding finger 16 which contacts with 85 the underside of the paper. The finger 15 is held against the paper with a yielding pressure by means of a spring 17 on a swinging rod 18 pivoted at 19 to the frame of the machine. The connection between the adjustable guide 13 and the swinging rod 18 is made by means of a pivoted block 20 in which the rod 18 is free to slide, and against the upper side of which the spring 17 presses, the other end of the spring being held in 90 place by a thumb screw 21. It will be seen from the drawing, that pivot 14 is at the rear of the pivot 19, and that, therefore, the adjustable guide will remain in the position shown in dotted lines in Fig. 5 when thrown 95 back. This device forms a convenient means for placing the proper tension upon the paper at this point and at the same time one which may be instantly moved out of the way when it is necessary to thread the paper 100 through the machine.

After leaving the adjustable guide 13, the web of paper 12 passes over the paste roll 22 which deposits paste or other suitable adhesive from the paste pan 23 upon the 110

under-surface of the web of paper. The paste pan 23 is preferably provided with some heating means, such as the steam pipe 24.

- 5 After leaving the paste roll 22, the web of paper passes between two guide rolls 25 and 26 supported adjacent each other on the frame. The roll 25 also distributes the adhesive evenly over the surface of the paper.
- 10 The paper then passes to the severing mechanism which will be later described by a route of variable length so that the paper may be exposed to air long enough to render the adhesive tacky. On the back of the 15 frame of the machine are brackets 27 one of which is shown in Fig. 1, which are each provided on their upper surface with a plurality of bearings 28, 29 and 30. At the rear end of these brackets 27 is pivotally 20 secured a pair of arms 31 each containing a plurality of notches 32, 33, which themselves form bearings to receive a guide roll over which the paper 12 passes. The arms 31 are capable of being swung about pivots 25 34 and secured in place in any desired position by means of thumb screws 35. If it is desired to expose the paper to the air for a considerable period of time, the parts are placed in the position shown in Fig. 1, that 30 is the guide roll 36 is placed in the bearings 29 and another guide roll 37 is placed in the notch 33, the web of paper 12 being fed from the guide roll 26, over the guide roll 36 and then around the guide roll 37 to the severing 35 mechanism. This position of the web of paper is shown in Fig. 1, in full lines. If a short period of time is required to dry the adhesive employed sufficiently the guide roll 36 is placed in the bearings 28 and the guide 40 roll 37 in the notches 32, the arms 31 being placed in a substantially vertical position, all as shown in dotted lines in Fig. 1. As will be readily seen, various other combinations may be made with these parts according 45 to the length of time required to render the adhesive fit for application.

Just before passing to the severing mechanism, the web of paper passes over a guide roll 38 with which coöperates a stop finger 50 39 secured on a cross rod 40. The stop finger 39 holds the paper against the roll 38 sufficiently firmly so that after the paper has been severed, it will not be drawn back by the weight of the paper between the 55 guide roll 38 and the guide roll 37.

At 42 is shown a rest upon which the work is placed. The position of the work is determined by a movable side guide 43, see Fig. 3, and a front guide 44, see Fig. 4. 60 The said rest 42 is secured to a bracket 45 by means of the clamp screws 46 and the bracket 45 is itself adjustably secured to a swinging member 47 which is hung from a pivot 48 on the frame of the machine. The 65 vertical adjustment of the bracket 45 on the

member 47 by means of the clamp screw 49 provides for raising or lowering the rest 42 for different depths of boxes or tops to be topped. The swinging member 47 is connected by a link 50 to a lever 51 pivotally secured at 52 to the frame of the machine. A spring 53 is secured to a rearwardly extending portion of the lever 51 and serves to restore the parts to normal position which is the position shown in Fig. 4. The pivot 70 48 is exactly on a level with the cutting line of the knives so that when the rest is depressed to sever the paper it swings about the cutting line, as an axis and the paper is not drawn out as the cutting takes place. 75 Also while the rest is for convenience of operation slightly inclined, the bracket 45 makes an exact right angle so that when the level of the rest is changed for different thicknesses of tops the corner of the top will 80 bear exactly the same relation to the cutting point as before the adjustment was made. By this means the machine may be set for any thickness of top, without changing the margin which is the amount which the end 85 of the covering paper falls short of the edge of the box, this being effected by changing the position of the front stop 44 by the hand clamp 46.

The two knives which sever the paper are 95 designated 54 and 55, and are secured to two pairs of arms 56 and 57, each pair of arms being mounted on the same pivot 58 and 59 respectively. The knives 54 and 55 are inclined as shown in Figs. 2 and 6 so 100 that the cutting of the paper begins on the right hand side of the sheet and the cutting point travels across from right to left, as shown in Fig. 2. The lever 51 is connected to the right hand upper knife arm 56 105 (viewed from the front of the machine) by a link 60 while the right hand lower knife arm 57 is likewise connected to the said lever by the link 61, the point of connection of the link 61 being below that of the link 60. Therefore when the lever 51 swings it moves the upper knife 54 a greater distance than it does the lower knife 55. Therefore if the two knives were both given the same 110 inclination the cutting point, as it travels, across the paper, would not be always on the same level. Accordingly, the lower knife is given a less inclination than the upper knife and the difference in inclination between the two halves is proportioned 115 to the difference in distance which they are moved by the lever 51 so that the cutting point is always on the same level as it travels across the paper. By constructing the parts as described, it is possible to have both knives moved by one lever thus avoiding a complicated mechanism but obtaining the desired action of the knives.

At 62 is shown a cross rod which forms a support for the end of the paper after it has 120

been severed so that the end of the paper may be conveniently seized by the operator to draw it forward for the next box. It will also be seen that while it is necessary for the operator to reach between the knives to seize the end of this paper, there is no danger to the operator in so doing, because it is necessary to employ both hands to press the paper down on the corners of the box which pressure causes the knives to come together to sever the paper, and therefore the hands are both necessarily out of the way before the knives can be brought together. The machine therefore may be operated with perfect safety.

At 63 there is shown a cap screw in a portion of the frame of the machine which serves as an adjustable stop to determine the position of the box rest in its normal position, this being the position shown in Fig. 4.

What I claim is:

1. The improved paper box machine comprising a pair of pivoted knife jaws each having an inclined edge, a lever and links from each of said knife jaws to said lever, one of said links connecting with said lever at a point farther from the fulcrum of the lever than the other, the knife jaw which is connected to said lever at the point farther from the fulcrum of the lever having a greater inclination than the other knife jaw.

2. The improved paper box machine comprising a pair of pivoted jaws each having an inclined edge, a lever and links from each of said knife jaws to said lever, one of said links connecting with said lever at a point farther from the fulcrum of the lever than the other, the knife jaw which is connected to said lever farthest from the fulcrum of the lever having an inclination greater than the other knife jaw, said difference in inclination between the two knife jaws being proportional to the difference in distance of the respective points of connection from the fulcrum of the lever.

3. The improved paper box machine comprising a movable work support, a pair of pivoted knife jaws each having an inclined edge, a lever, connections from the work support to the lever whereby a downward movement of the work support will move the lever, a pair of pivoted knife jaws each having an inclined edge, and links from each of said knife jaws to said lever, one of said links connecting with said lever at a point farther from the fulcrum than the other and the knife jaw which is connected to said lever at the point farthest from the fulcrum of the lever having a greater inclination than the other knife jaw.

4. The improved paper box machine comprising a pair of jaw knives, a swinging support operatively connected to said jaw knives, means for holding said support normally in a given position, said support being pivoted substantially on a line between the cutting line of said jaw knives and the outer end of said support when in its normal position.

5. The improved paper box machine, comprising a pair of jaw knives, a swinging frame pivoted closely adjacent the cutting line, a work support secured to said frame, and means for operating said jaw knives by the movement of said swinging support.

6. The improved paper box machine comprising a pair of jaw knives, a swinging frame pivoted to the frame of the machine and adjacent the cutting line, a work support at right angles with the swinging frame, means for adjusting the work support lengthwise of said swinging frame and connections from said swinging frame to said jaw knives.

In testimony whereof I affix my signature, in presence of two witnesses.

EUGENE H. TAYLOR.
